UNITED STATES PATENT OFFICE.

JOSEPH E. GADBOIS, OF SPRINGFIELD, MASSACHUSETTS.

DENTAL-FLASK HOLDER.

1,410,291.

Specification of Letters Patent. Patented Mar. 21, 1922.

Application filed November 27, 1920. Serial No. 426,880½.

To all whom it may concern:

Be it known that JOSEPH E. GADBOIS, a citizen of the United States of America, residing at Springfield, in the county of 5 Hampden and State of Massachusetts, has invented certain new and useful Improvements in Dental-Flask Holders, of which the following is a specification.

This invention relates to improvements in 10 means for holding dental flasks in vulcanizers to insure accurate molding of the work, and its leading object is to provide a device of this character which can be quickly adjusted so as to hold one or a number of 15 flasks in clamping position in the vulcanizer, and is capable of yielding under excessive pressure within the flask due to the heating of the contents thereof, and this without diminishing the clamping pressure.

20 Another object of the invention is to provide a device of this character with means for preventing the follower from yielding or warping and the uprights or guides from spreading apart.

25 With the above and other objects in view this invention relates to certain new and useful constructions, combinations and arrangements of parts, clearly described in the following specification and fully illustrated 30 in the accompanying drawings, in which:

Figure 1 is a side elevation.

Figure 2 is a top plan view.

Figure 3 is a horizontal sectional view taken on line 2 of Fig. 1.

35 Figure 4 is a detail in vertical section of certain of the clamping elements.

Referring to the accompanying drawings 5 designates a metal base to opposite sides of which are secured the standards or vertical guides 6 and 7, each being provided 40 with a series of notches or recesses 8 providing spaced teeth or lugs 9.

On the upright guides 6 and 7 a follower plate 10 is slidably mounted, said follower 45 plate having openings 10^a provided in ears 11, and said ears being formed with depending extensions 11^a engaging the outer faces of the guides 6 and 7 so as to brace said follower plate and insure the correct vertical 50 movement thereof without tilting and interlocking with the lugs or notches described. Each of the uprights may also be provided with a V shaped rib or edge portion 12 whereby the follower will be held against 55 lateral movement on the uprights, said fol-

lower being formed with corresponding grooves.

The follower plate 10 is provided with a central opening through which a clamping screw 13 extends. The lower end of this 60 clamping screw has a collar 14 swiveled thereto and the upper end carries a head 15 whereby the screw may be operated, said head being formed with transverse openings or the like. The screw 13 is in threaded engagement with nuts 16 and 20 between which the composite spring 17 is suitably clamped. The spring 17 has arms 17^a curved against the under side of the plate 10 and the spring is held against relative movement on 70 the follower plate by means of pins 18 secured to said plate. A pin 21 passes through the plate 10 and the spring 17 at a point adjacent to the nuts 16 and 20, and is headed over at both ends. This pin retains the 75 spring 17 with its arms 17^a in contact with the plate 10, but does not interfere with the required compression and expansion of said spring. The screw 13 is loose in the follower plate, and a cross bar 19 loosely mounted 80 on said screw above said plate and adapted to be moved into interlocking relation with the lugs or notches of the uprights 6 and 7.

In practice, the follower 10 with attached 85 parts is raised a sufficient distance to permit a flask to be placed on the base 5, and then said follower is lowered until the collar 14 and the base of the clamping screw 13 come to rest on top of said flask; next 90 said follower is locked in position by means of the bar 19 which is partially rotated on its axis into engagement with two of the teeth 9; and, finally, said screw is rotated in the direction to actuate the same downwardly in the nuts 16 and 20 to the required extent. As the screw 13 is turned down it 95 fulcrums on or has its bearings in the nuts 16 and 20, and with the collar 14 is forced tightly against the top of the flask, the 100 spring 17, bearing as it does at the ends on the now locked follower, yielding to an extent commensurate with the force exerted on said screw after the same contacts with the flask. Any pressure in the flask, which is 105 sufficient to overcome the resistance of the spring which holds the screw down on said flask, is relieved by the yielding of said spring, and immediately after such pressure has been relieved said spring expands again 110

to restore the parts to their former positions and conditions.

To release the flask it is simply necessary to turn up the screw 13 far enough to remove the tension from the spring 17, swing the bar 4 out of engagement with the teeth 9, and raise the follower 10, when said flask can be taken from the base 5.

Having described my invention I claim:

10. 1. A dental flask holder comprising rigidly connected uprights, a follower slidably arranged on said uprights, means to lock said follower to said uprights, a clamping screw, and resilient means for attaching said screw to said follower.

20. 2. A dental flask holder comprising rigidly connected uprights, a follower slidably arranged on said uprights, means to lock said follower to said uprights, resilient means supported from and bearing against said follower, and a clamping screw in engagement with said resilient means, and adapted to exert a yielding pressure on an object engaged by said screw.

30. 3. A dental flask holder comprising rigidly connected uprights, a follower arranged to slide on said uprights, means to lock said follower to said uprights, resilient means supported from and bearing against said follower without being deprived of the required amount of expansion and contraction, and a clamping screw in engagement with said resilient means, and adapted to exert a yielding pressure on an object engaged by said screw.

40. 4. A dental flask holder comprising rigidly connected uprights, a follower arranged to slide on said uprights, means to lock said follower to said uprights, resilient means supported from and bearing against said follower, means to hold said resilient means against independent rotation relative to said follower, and a clamping screw in engagement with said resilient means, and adapted to exert a yielding pressure on an object engaged by said screw.

50. 5. A dental flask holder comprising rigidly connected uprights, a follower arranged to slide on said uprights, means to lock said follower to said uprights, resilient means supported from said follower without being deprived of the required amount of expansion and contraction, means to hold said resilient means against independent rotation relative to said follower, and a clamping screw in engagement with said resilient means, and adapted to exert a yielding pressure on an object engaged by said screw.

60. 6. A dental flask holder comprising rigidly connected uprights, a follower slidably

arranged on said uprights, means to lock said follower to said uprights, resilient means supported from and bearing against said follower, and a clamping screw provided at one end with a swivel plate, said screw being in engagement with said resilient means, and adapted to exert a yielding pressure on an object engaged by said screw.

7. A dental flask holder comprising rigidly connected uprights, a follower arranged to slide on said uprights, means to lock said follower to said uprights, a spring below said follower, said spring having arms to bear against the follower, which latter is provided with projecting members to hold said spring against independent movement relative thereto, and a clamping screw in engagement with said spring, and adapted to exert a yielding pressure on an object engaged by said screw.

8. A dental flask holder comprising rigidly connected uprights, a follower arranged to slide on said uprights, a spring having arms adapted to bear against said follower, washers on opposite sides of said spring, means to secure said spring and washers together, a clamping screw passing loosely through said follower and in threaded engagement with said washers, and means to hold said spring against rotation relative to said follower.

9. The combination, in a dental flask holder, with a base, and serrated posts rising from said base, of a follower arranged to slide on said uprights, resilient means carried by said follower, a screw passing loosely through said follower and into threaded engagement with said means, and a locking bar mounted on said screw above said follower, and adapted to be engaged with and disengaged from the serrations in said post.

10. The combination, in a dental flask holder, with a base, and serrated posts mounted on said base, of a follower having perforations therein to receive said posts, and being adapted to slide up and down thereon, resilient means carried by said follower, a screw passing loosely through said follower and into threaded engagement with said means, and a locking bar mounted on said screw above said follower to engage and disengage the serrations in said posts, said bar being adapted when in engagement with said serrations to hold said follower against upward movement.

Signed by me at Springfield, Massachusetts.

JOSEPH E. GADBOIS.
